WILLIAM G. LEWIS, OF LOS ANGELES, CALIFORNIA.

WATER HEATER.

1,418,812.

Specification of Letters Patent. Patented June 6, 1922.

Application filed July 22, 1920. Serial No. 398,216.

To all whom it may concern:

Be it known that I, WILLIAM G. LEWIS, a citizen of the United States, residing at Los Angeles, in the county of Los Angeles and 5 State of California, have invented new and useful Improvements in Water Heaters, of which the following is a specification.

This invention is a water heater of the type adapted to quickly heat a supply of water whenever a faucet of the system is turned on.

It is the object of the invention to provide improved means for automatically lighting the burner of the heater whenever 15 water is withdrawn from the system, said means being of simplified construction but positive and efficient in its action.

It is a further object of the invention to provide an improved water chamber through 20 which the products of combustion from the burner pass in order to heat the water, said chamber being arranged to bring the products of combustion into close relation to the water in order that a relatively large quantity thereof may be rapidly heated.

The invention will be readily understood from the following description of the accompanying drawings, in which—

Figure 1 is a longitudinal section through 30 the burner of the heater.

Fig. 1^A is a similar section through the water chamber mounted upon the upper end of the burner.

Fig. 2 is a transverse section on the line 35 2—2 of Fig. 1^A.

Fig. 3 is a top plan view of the burner.

The heater consists essentially of a burner, preferably, of cylindrical shape upon the upper end of which is mounted a water 40 chamber which is also, preferably, of cylindrical shape.

The burner chamber 1 is provided with an intermediate transverse partition 2 through which extends a discharge port 3 for the fuel of the burner. A valve 4 is arranged to close the port 3 and is provided with a depending valve stem 5 extending downwardly through the burner chamber and guided in a suitable bearing 6 formed as a 45 transverse partition 6^A, at the lower end of the burner chamber. A piston 7 fitting snugly within the chamber beneath the partition 6^A is mounted upon the lower end of

valve stem 5 below the bearing 6. A spring 8 preferably an expansive coil spring is arranged beneath piston 7 for normally forcing the latter and valve 4 upwardly so that the valve will seat in order to close port 3.

The chamber between piston 7 and partition 6^A is provided with a water inlet pipe 9, and a similar water discharge pipe 10 extends from the opposite side of said portion of the chamber. The pipe 9 communicates freely with the interior of the water chamber beneath partition 6^A while the opening from the latter into pipe 10 consists of a port 11 restricted in size. Beyond port 11 the pipe 10 communicates with the portion of the water chamber below piston 7 as through a restricted by-pass 12 communicat- 65 ing at the port 13 with pipe 10 and at the port 14 with the water chamber above piston 7.

A fuel inlet pipe 15 communicates with the portion of the burner chamber between partitions 2 and 6, and a pipe 16 controlled by a manually operated valve 17 leads from this portion of the burner chamber and terminates in a pilot light nozzle 18 arranged above the upper end of the burner chamber. The upper end of the burner chamber is provided with the discharge opening 19 for fuel from the burner, and a screen 20, preferably extends across the burner chamber below the discharge opening 19 in order to prevent the 80 flames of the burner passing downwardly into the burner chamber. A suitable opening 21 is provided in the burner chamber above the fuel port 3 for supplying the necessary air to support combustion.

The cylindrical water chamber of the heater is shown at 23 as extending longitudinally beyond the upper end of the burner chamber, said water chamber being provided with a suitable flange 24 secured to the burner chamber. The water chamber is provided with open ends and a plurality of spaced water passages extending lengthwise through the water chamber. The water passages are shown as two annular chambers 90 25 and 26 arranged at opposite sides of the water chamber. Each of these water passages are formed between concentric pipes 27 and 28 having the ends of the annular passage formed between said pipes closed by 100 105 the end walls 29 and having the passage

through the inner pipe 27 open at its respective ends.

The two water passages 25 and 26 are, preferably, connected by a pipe 30 at the upper 5 ends of the pipes forming said water passages, and a pipe 31 leading from a source of water supply communicates with the lower end of one of the water passages, say the passage 26, while the end of pipe 9 communicates with the lower end of the opposite 10 water passage 25. The pipes 27 and 28 forming the water passages and connected as thus described may be supported within the cylinder 23 in spaced relation from the sides 15 thereof upon a suitable annular bracket 32. The parts, as thus described, are so arranged that the flames of the burner above the upper end of burner chamber 1 will be projected upwardly through the passages 33 20 formed through pipes 27 and also through the passage 34 formed between cylinder 23 and pipes 28, as well as though the central passage 35 formed between the respective pipes 28. The body of water within passages 25 and 26 will thus be completely surrounded by the products of combustion from the burner for causing ready heating of said water.

Baffles are, preferably, provided across 30 the passages for the products of combustion through the water chamber in order to divert said products of combustion for enabling the greater portion of the units thereof to be utilized in heating the water in 35 passages 25 and 26. These baffles are arranged one beyond the other throughout the length of the water chamber and are shown as each comprising a disc 36 extending across the water chamber and terminating 40 ing short of the wall 23 thereof.

The disc 36, preferably, comprises two plates 36^a and 36^b at opposite sides of the water chamber, each of said plates being provided with a central recess 37 and with 45 openings 38 so arranged as to permit the plates to be received over the pipes 27 and 28. The recesses 37 of the co-operating plates forming one of the baffle discs provide a central aperture through the baffle 50 for the passage of the products of combustion, while the plates of a baffle disc form means for diverting a portion of the products of combustion outwardly around pipes 27 and 28. The baffle discs are, preferably, 55 dished, as clearly shown in the drawings, with the peripheral portions thereof extending downwardly from the central portions of said baffle discs in order to divert the products of combustion downwardly during their passage around pipes 27 and 28 and before their final discharge through the passage 34 to the open upper end of the water chamber.

When the water heater is in use, water 65 supplied through pipe 31 will fill passage

26 and then flow through pipe 30 to fill passage 25. From thence the water flows through pipe 9 into the pressure chamber 40 between piston 7 and partition 6, and also by way of by-pass 12 into the pressure chamber 41 below piston 7.

When all of the faucets leading from the discharge pipe 10 are closed, a balanced pressure is thus obtained in chambers 40-41 and spring 8 as a consequence will close 75 valve 4 for cutting off the fuel supply and thereby prevent operation of the heater. As soon, however, as one of the faucets leading from pipe 10 is opened, the restricted port 11 preventing the free flow of water from chamber 40, will cause the pressure in said chamber to exceed the pressure in chamber 41, and as a consequence the tension of spring 8 will be overcome and the piston 7 will be moved downwardly so as to open valve 85 4 and thereby permit the flow of fuel through the end 19 of the burner chamber and past the pilot light, for igniting the same. The products of combustion thus formed will pass through the water chamber as previously described for quickly heating the water in its passage therethrough.

Various changes may be made without departing from the spirit of the invention as claimed.

What is claimed is:

1. In a water heater, a cylindrical housing provided with partitions that divide the space within said housing into a burner chamber, a gas chamber and a water chamber, the partition between the gas chamber and the burner chamber being provided with a gas outlet, a valve stem arranged for sliding movement through the partition between the water chamber and the gas chamber, a valve carried by the upper end of said stem and adapted to normally close said gas outlet, a piston arranged for operation within the water chamber and connected to the lower end of the valve stem, a water inlet to the water chamber above the piston, and restricted water outlet openings leading from the water chamber above and below the piston therein.

2. A water heater having a burner chamber and a gas chamber, a valve for controlling the flow of gas from said gas chamber to said burner chamber, a piston connected to said valve, a pressure chamber at each side of said piston, a spring in one of said chambers for normally closing said valve, a water inlet to the other of said chambers and a restricted water discharge therefrom, a pilot light tube leading from the gas chamber to a point above the burner chamber, and a by-pass from said water discharge to the first of said pressure chambers.

3. A water heater having a burner chamber and a gas chamber, a valve for controlling the flow of gas from said gas cham-

ber to said burner chamber, a piston connected to said valve, a pressure chamber at each side of said piston, a water inlet and a water discharge from one of said pressure chambers, and a by-pass from said water discharge to the second of said pressure chambers, the parts being so arranged that open-

ing of said water discharge will cause a variation in pressure in the respective pressure chambers for actuating said piston to open 10 said valve.

In testimony whereof I have signed my name to this specification:

WILLIAM G. LEWIS.
